Atty.

UNITED STATES PATENT OFFICE

WILLIAM R. UHLEMANN, OF CHICAGO, ILLINOIS, ASSIGNOR OF TWO-THIRDS TO
RICHARD H. UHLEMANN, OF CHICAGO, ILLINOIS

GLARE DIMMER ATTACHMENT

Application filed April 26, 1932. Serial No. 607,563.

This invention relates to that type of glare dimming or like accessories adapted for attachment to a pair of eye-glasses or spectacles in a pivotal manner in order to be swung 5 up and out of the range of the eyes of the wearer during temporary non-use of the appliance. And this improvement has for its object:

To provide a structural formation and association of parts in a glare dimmer or like attachment for spectacles, embodying the features of lightness, durability and cheapness in manufacture combined with a ready, convenient and firm mounting of the attachment in proper relation on the lens or lens frame of the spectacles and in a readily detachable manner, all as will hereinafter more fully appear.

In the accompanying drawing:—
20 Fig. 1 is a rear elevation of the preferred form of the invention, with the spectacles to which it is applied shown in dotted lines.

Fig. 2 is a top view with the carrying spectacles shown in dotted lines.
25 Fig. 3 is an enlarged section of the attachment on line 3—3 of Fig. 1.

Like reference numerals indicate like parts in the different views.

As shown in the drawing, the dimmer 30 member of the attachment is formed from a comparatively thin sheet of material, such as celluloid, and comprises a pair of counterpart portions 1 and 2, of any usual form arranged in spaced relation to each other to 35 provide the required nose gap 4. In the preferred construction shown in Fig. 1 the two portions 1, 2, are integrally connected together by a central connecting portion 3; it is however within the scope of the invention 40 to dispense with this connecting portion and form the portions 1, 2, as separate units.

In either case each portion 1 and 2 will be formed with a straight marginal edge for substantial attachment in an associated holder or base member 5 of a detail construction 45 now to be described.

The holder 5 is formed from a strip of metal folded upon itself in the form of a flattened return bend so as to provide a narrow channel for the reception of the above

mentioned straight marginal edges of the dimmer sections 1 and 2, which are fixed therein by rivets or other usual fastening means. Midway the transverse extent of the holder 5 the same is provided with a pivot 55 sleeve 6 preferably formed by a circular bend in the sheet metal of the holder. Said pivot sleeve is adapted to afford pivotal connection between the holder 5 and a resilient attaching member 7, by means of which detachable 60 connection of the attachment to a pair of spectacles, is had in a ready and substantial manner.

In the present improvement the resilient 65 attaching member 7 above referred to, is formed of a length of round spring wire bent into an open and approximately oval form, the middle portion of which has pivotal engagement in the pivot sleeve 6 of the holder 70 5 aforesaid, and held from independent longitudinal shift therein by fixed collars 8 having abutment against the respective ends of said pivot sleeve, while the respective curved or hook shaped end portions 9 and 10 of the attaching member are adapted to engage the outer margins of the lens or the lens frames 75 of the pair of spectacles to which this attachment is applied.

To the above end each hook shaped side portion 9 and 10 of said resilient attaching 80 means is provided with a plurality of clip members 9', 10' in spaced relation and of an angular formation adapted to provide holding recesses to receive and engage the outer 85 portions of the spectacles lens at points above and below the pivotal attachment of the usual temple rods or bows of the spectacles to attain a substantial yet readily detachable connection of the parts.

With such construction, the connection is maintained by the resilient nature of the attaching means, which permits of the ready spreading apart of the hook shaped end portions 9 and 10 in the operation of applying 95 the attachment to the spectacles, and due to such resilient nature cause said end portions to move towards each other with their clips 9', 10', in holding engagement with the lens frame of the spectacles.

Having thus fully described my invention what I claim as new, is:—

1. In a spectacle attachment of the type herein described, the combination of a dim-
5 mer member of sheet material, a sheet metal holder for said member folded along its length into a flattened return bend provided at its mid-length with an integrally formed pivot sleeve, and an attaching member
10 formed of resilient wire pivotally mounted at its middle in the aforesaid pivot sleeve, said attaching means being of an open and approximately oval shape providing hook shaped outer portions with each of said por-
15 tions carrying clips in spaced relation and adapted for engagement with the lens or lens frame of a pair of spectacles in straddle relation to the attaching lugs thereof for the temple bows.
- 20 2. In a spectacle attachment as specified in claim 1, and wherein the attaching member is provided with stop collars for abutment against the respective ends of the pivot sleeve to hold the parts from individual shift.
- 25 In testimony whereof I hereunto affix my signature.

WILLIAM R. UHLEMANN.
